United States Patent Office

Des. 181,642
Patented Dec. 10, 1957

181,642

EXERCISER

Elizabeth Nightingale Graham, New York, N. Y.

Application June 6, 1956, Serial No. 41,774

Term of patent 14 years

(Cl. D83—1)

Fig. 1.

Fig. 2.

Fig. 3.

Fig. 1 is a side elevational view of an exerciser embodying my new design,

Fig. 2 is a side elevational view of the opposite side of the exerciser, and

Fig. 3 is an end elevational view.

The article is substantially round in cross sectional configuration throughout its length.

I claim:

The ornamental design for an exerciser, substantially as shown and described.
